INVENTOR.

Bertram S. Wright

BY *George W. Lister*
ATTORNEY

UNITED STATES PATENT OFFICE.

BERTRAM S. WRIGHT, OF SACRAMENTO, CALIFORNIA.

NONGLARE LENS.

Application filed March 12, 1923. Serial No. 624,335.

To all whom it may concern:

Be it known that I, BERTRAM S. WRIGHT, a citizen of the United States, residing at Sacramento, county of Sacramento, State of California, have invented certain new and useful Improvements in Nonglare Lenses; and I do declare the following to be a full, clear, and exact description of the same, reference being had to the accompanying drawings, and to the characters of reference marked thereon, which form a part of this application.

This invention relates to improvements in lenses for headlights, especially those of motor vehicles, the principal object being to provide a lens, applicable to any standard form of headlight and reflector, which will act to throw the light from the lamp downwardly and concentrate the same on the road ahead of the vehicle, doing away with the upwardly projecting beams which are the cause of glare in the eyes of persons ahead, such a glare being very evident in a great many headlights now in use, and a source of annoyance to those forced to look at the lights and the direct cause of many accidents.

At the same time, the necessary side-light on the road, by which the driver can see the curbing or edge of the road is maintained to an efficient degree, and the device is so constructed that there are no dark places or shadows between the light thrown ahead and that thrown to the sides, such as are very frequently noticed with various lenses.

Another object is to provide a lens structure in which plain glass may be used, and which can be installed or changed in the same time necessary to install an ordinary glass lens, and without necessitating any changes being made to the reflector, clamping rim, or other parts of the headlight.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of ref-

erence indicate corresponding parts in the several views.

Fig. 1 is a sectional view of the lens, 55 showing the same installed in a headlight.

Fig. 2 is an inner or rear view of the lens detached.

Fig. 3 is an enlarged fragmentary cross-section on the line 3—3 of Fig. 2. 60

Referring now more particularly to the characters of reference on the drawings, the numeral 1 denotes in general a headlight, having the usual reflector 2 and centrally located lamp 3. 65

My improved lens comprises a plain glass disc 4 held in place by the usual clamping rim 5 of the headlight.

On the inner face of the disc is a flat opaque plate 6, preferably of thin sheet 70 metal. This plate is located on the upper half of the disc, though extending slightly below the horizontal center line thereof, which is also in the central plane of the lamp 3. 75

A portion of said plate, from its lower edge upwardly for a certain distance, is cut away as at 7, the sides of said opening being vertical and equal distances on each side of the vertical center line of the lamp, 80 while the upper edge is preferably curved on an arc whose center is below the center of the disc and therefore has a greater radius than the disc. A short flange 8 projects inwardly from the plate and follows the outline of the opening 7. 85

Projecting inwardly from the plate and disc to a point adjacent the reflector 2 is a hood 9, following the three sides of the opening 7 and secured to the plate by fastening 90 onto the flange 8 by welding or any other similar means. The sides of the hood are straight and parallel to each other, while the top is curved the same as the upper edge of the opening 7 and slopes upwardly and rearwardly from said opening to its termination adjacent the reflector 2. 95

In order to mount the plate 6 onto the disc 4 so that an even thickness all around the rim of the disc will be had, I extend the plate 100 around the lower half of the disc adjacent the periphery thereof in the form of a narrow strip or ring 10. The plate and strip are then permanently secured onto the glass

by any suitable means, such as a circular strip or gasket of tape 11 or other fabric, glued on both sides, which is interposed between the metal member and the glass, and 5 the three parts then firmly pressed together. This operation is done in the factory, so that the buyer purchases the lens structure as a single unit, ready to be installed in the same manner as an ordinary glass lens.

10 The inner surfaces of the plate and hood are dulled so as to kill any reflecting power they may have, as by aluminum paint or otherwise.

By the use of this opaque plate, in connection with the hood or light-well 9, into which the lamp 3 of course projects, I have found from extensive trials in actual practice that a very fine light on the road is obtained, both ahead of and to one side of the headlight, 20 and all glare above the horizontal center of the lamp, is entirely eliminated.

From the foregoing description it will be readily seen that I have produced such a device as substantially fulfills the objects of 25 the invention as set forth herein.

While this specification sets forth in detail the present and preferred construction of the device, still in practice such deviations from such detail may be resorted to as do not form a departure from the spirit of the 30 appended claims.

Having thus described my invention, what I claim as new and useful and desire to secure by Letters Patent is:

35 1. A lens for headlights including an opaque plate mounted in front of and above the horizontal center line of the lamp of the headlight, said plate having a transversely central opening extending upwardly from the lower edge thereof, and a hood around

said opening extending inwardly of the plate to and about the lamp, said hood being open along the bottom.

2. A lens for headlights including an opaque plate mounted in front of and above the horizontal center line of the lamp of the headlight, said plate having a transversely central opening extending upwardly from the lower edge thereof, and a hood around 45 said opening extending inwardly of the plate to and about the lamp, the sides of said hood being parallel to each other while the upper face of the hood slopes upwardly towards the rear.

3. A lens for headlights including an opaque plate mounted in front of and above the horizontal center line of the lamp of the headlight, said plate having a transversely central opening extending upwardly from the lower edge thereof, and a hood around 50 said opening extending inwardly of the plate to and about the lamp, and terminating at its rear edges adjacent the reflector of the lamp, the inner surface of said hood being non-reflecting.

4. A lens for headlights including an opaque plate mounted in front of and above the horizontal center line of the lamp of the headlight, said plate having a transversely central opening extending upwardly from 55 the lower edge thereof, and a hood around said opening extending inwardly of the plate to and about the lamp, the sides of said hood being parallel to each other while the upper face of the hood slopes upwardly 60 towards the rear, and is curved on an arc whose center is below the plane of the lamp.

In testimony whereof I affix my signature.

BERTRAM S. WRIGHT.
